United States Patent Office

Des. 196,604
Patented Oct. 15, 1963

196,604

NAVIGATION PLOTTER

James W. Keck, Tokyo, Japan (Southern Air Transport,
APO 323, % Postmaster, San Francisco, Calif.)

Filed Nov. 30, 1962, Ser. No. 72,670

Term of patent 14 years

(Cl. D52—6)

FIGURE 1 is a top plan view of a navigation plotter showing my new design;

FIGURE 2 is a top edge elevational view thereof; and

FIGURE 3 is an end elevational view thereof.

The rear of the navigation plotter is substantially plain in appearance.

I claim:

The ornamental design for a navigation plotter, as shown and described.
